UNITED STATES PATENT OFFICE.

JOSEPH KINTZ, OF WEST MERIDEN, CONNECTICUT, ASSIGNOR TO HIMSELF AND
P. J. CLARK, OF SAME PLACE.

DESIGN FOR A MATCH-BOX.

Specification forming part of Design No. 5,428, dated December 19, 1871.

Specification describing a Design for a Box for Matches and other uses, invented by JOSEPH KINTZ, of West Meriden, in the county of New Haven and State of Connecticut.

The nature of my design is fully represented in the accompanying drawing, to which reference is made.

The body of the box A is made semi-cylindrical or thereabout, and the ends B are rounded and fluted, as shown. The plain surface between the ends is coated with sand when the box is to be used for matches. The cover is made straight on the back at C, where it is hinged to the back G, and from the said straight part around the ends and front it follows the shape of the body

of the box except at the center, where a slight projection, E, is formed. F is a diaphragm in the cover, having the same form as that of the edge of the cover. The back G approximates a triangular form, with a raised rib, H, along the margin, and terminating in a ring, I, at each corner of the case.

I claim as my invention—

1. The design for the body of the box, as shown.
2. Also, the design for the cover, as shown
3. Also, the design for the back, as shown.

JOSEPH KINTZ.
